UNITED STATES PATENT OFFICE

106,000

DESIGN FOR A TIRE

Harry M. Pryale, Pontiac, Mich.

Application November 4, 1935, Serial No. 59,385

Term of patent 3½ years

To all whom it may concern:

Be it known that I, Harry M. Pryale, a citizen of the United States of America, residing at Pontiac, in the county of Oakland and State of Michigan, have invented a certain new, original, and ornamental Design for a Tire, of which the following is a specification, reference being had therein to the accompanying drawing, forming a part thereof, in which

Figure 1 is a side elevational view of a tire having a section showing my new design illustrated on full lines;

Figure 2 is a perspective view, partly in section, of the design shown in Figure 1; and

Figure 3 is a sectional view taken substantially on the plane indicated by the line 3—3 of Figure 1.

The dominant feature of my design for a tire consists in the provision of circumferentially spaced markings on the side walls of the tire extending inwardly from the outer circumference of the tire.

I claim:

The ornamental design for a tire, substantially as shown and described.

HARRY M. PRYALE.
